UNITED STATES PATENT OFFICE.

HENRY ORSENIGO, OF MOUNT VERNON, NEW YORK.

DESIGN FOR A COMBINED LAMP AND NEEDLE HOLDER FOR PHONOGRAHS AND THE LIKE.

Application filed August 25, 1923. Serial No. 7,092. Term of patent 7 years.

To all whom it may concern:

Be it known that I, HENRY ORSENIGO, a citizen of the United States, residing at Mount Vernon, county of Westchester, State of New York, have invented a new, original, and ornamental Design for Combined Lamp and Needle Holder for Phonographs and the like, of which the following is a specification, reference being had to the accompanying drawing, forming part thereof.

The figure is a perspective view of a combined lamp and needle holder for phonographs, showing my new design.

I claim:

The ornamental design for a combined lamp and needle holder for phonographs and the like, as shown.

HENRY ORSENIGO.
